PROJECTION SCREEN OR SHADE
CONSTRUCTION

Orin N. Crider, Chicago Heights, Ill., assignor, by mesne assignments, to Slick Industrial Company, Chicago Heights, Ill., a corporation of Delaware
Filed Feb. 7, 1963, Ser. No. 256,992
3 Claims. (Cl. 160—23)

This invention relates to screen or shade constructions of the kind adapted to be mounted on a wall to serve as motion picture projection screens, maps, window shades, and the like, and more particularly the invention pertains to a screen or shade construction adapted to be stored in rolled or wound condition when not in use and having a self-contained housing adapted to receive the rolled screen and cover the latter when the screen is not in use.

Window shades, maps, motion picture projection screens, and the like, commonly include a sheet of flexible material secured at one of its ends to a rotatable member that is mounted at its opposite ends on a wall by brackets, the opposite end of the flexible sheet being free so as to permit the sheet to be unrolled and hang vertically when it is desired to make use of the sheet. Screen constructions of the general class to which the invention pertains conventionally include a bar or rod at the free end of the flexible sheet to prevent curling of the edges of the sheet and to weight the free end of the sheet so as to overcome the residual tendency of the sheet to assume a rolled configuration.

Maps, projection screens, and window shades conventionally are mounted by means of a bracket at each end of the roller member. Such brackets, therefore, are exposed to view unless some additional structure is utilized to conceal them. Many homeowners utilize valances at the tops of windows to conceal shade rollers, mounting brackets, and drapery rods, but such valances frequently are more expensive than the shades themselves. Moreover, it is not always practical to utilize valances, particularly in those instances when the rolled sheet is to be used as a map or motion picture projection screen.

An object of this invention is to provide a shade or screen construction having self-contained means for concealing the shade or screen and its mounting means when the shade or screen is not in use.

Another object of the invention is to provide apparatus for concealing a rolled shade or screen when the latter is not in use, such apparatus also serving to prevent curling and rolling of the shade or screen when the latter is in use.

A further object of the invention is to provide apparatus of the kind described which can be applied to shade and screen constructions already in production without modification of the shades or screens.

Another object of the invention is to provide apparatus of the character described which is inexpensive to manufacture and assemble, but durable in use.

Other objects and advantages of the invention will be pointed out in detail or will become apparent from the following description when it is considered in conjunction with the appended claims and the accompanying drawings, in which:

FIGURE 1 is a sectional plan view through a vertical wall and illustrating a shade or screen mounted on the wall in rolled condition;

FIGURE 2 is an elevational view of the mechanism shown in FIGURE 1;

FIGURE 3 is an end elevational view of one end of a shade or screen roller;

FIGURE 4 is a sectional view taken on the line 4—4 of FIGURE 2;

FIGURE 5 is a fragmentary view, partly in section

and partly in elevation, and illustrating the shade or screen unrolled for use; and

FIGURE 6 is an end elevational view illustrating one end of a housing constructed according to the invention and in the position it occupies when the shade or screen is unrolled for use.

Apparatus constructed in accordance with the disclosed embodiment of the invention comprises a conventional, cylindrical shade roller 1 comprising a cylindrical member 2 having a cavity 3 at one end thereof within which is located a spring biased winding mechanism 4 of known construction. The mechanism 4 may be of any conventional construction, such as that disclosed in Patent No. 2,173,791. Briefly, however, the mechanism 4 includes a spindle 5 that is notched at its inner end as at 6 to receive one end of a coil spring 7, the other end of the spring being anchored to a disk 8 which is secured to the cylinder 2 and closes the open end of the latter. Secured to the spindle 5 and rotatably extending through the disk 8 is a flattened spear 9 that is adapted to be received in a slot 10 formed in a bracket 11 having a mounting foot 12 which may be secured to a vertical wall 13 by means of screws 14. A toothed ratchet wheel W is fixed to the spear 9 adjacent the disk 8, and the latter is provided with pivotal ratchet pawls P which cooperate with the ratchet teeth to latch the cylindrical roller 2 against rotation by the spring 7. As is conventional, the pawls may be pivoted out of engagement with the teeth of the ratchet wheel to permit rotation of the roller 2 in either direction by the spring when desired.

The opposite end of the roller 2 is provided with a cylindrical spindle 15 that is adapted to extend through a circular opening formed in a conventional bracket 16 in the usual manner. The bracket 16 includes a mounting foot 17 which may be secured to the wall 13 by screws 18.

Associated with the roller construction 1 is a flexible sheet 19 formed of conventional cloth or plastic materials, in the case of window shades and maps, or formed of conventional light-reflective material in the case of a projection screen. One end 20 of the sheet 19 is secured to the roller member 2 by any suitable means, such as staples 21, and the opposite end 22 of the sheet is free of the roller so as to permit the sheet to be rolled upon itself about the roller, and unrolled.

All of the apparatus described thus far is conventional in shade, screen and map constructions, and forms no part of the invention except insofar as such apparatus cooperates with the structure yet to be described.

Apparatus constructed in accordance with the invention comprises a housing 23 composed of at least two elongated panel members 24 and 25 secured to one another in right-angular relation along corresponding edges so as to present a substantially L-shaped configuration in end elevation. Preferably, substantially square end panels 26 and 27 are secured to the members 24 and 25 at opposite ends thereof.

The free end 22 of the sheet member 19 may be turned under the main body of the sheet and secured to the panel 24 by suitable means such as staples 28. The free end of the sheet 19 is secured to the panel 24 between the side edges of the latter for a purpose which presently will be described.

The length of the panel members 24 and 25 should be greater than the overall length of the roller construction 1 from the free end of the spear 9 to the free end of the spindle 15 so as to permit the housing 23 to receive the entire roller and bracket assembly between its end walls 26 and 27. The sheet 19, therefore, should be centered with respect to the length of the housing so as to permit the latter to extend an equal distance beyond each side of the flexible sheet.

To condition the apparatus for use, the mounting brackets 11 and 16 are mounted on the wall 13 and the roller assembly 1 is mounted in the brackets in such manner that unwinding of the flexible material from about the roller causes the latter to rotate in a counterclockwise direction, as viewed in FIGURE 4. When the flexible sheet is unwound from the roller and hangs vertically, the free end 22 of the sheet will underlie the main body of the latter, due to the weight of the housing 23, and the wall 24 of the housing will extend in prolongation of the sheet 19 with the wall 25 lowermost, all as is indicated in FIGURES 5 and 6. When the housing 23 is suspended by the flexible sheet, the rigidity of the housing prevents the side edges of the sheet from curling toward one another, and the weight of the housing holds the sheet in a substantially vertical plane and overcomes the tendency of the sheet to roll.

When it is desired to store the flexible sheet in rolled condition, a downward tug on the sheet will release the latch pawls and permit the spring 7 to rotate the roller and roll the sheet upon itself about the roller, causing the housing 23 to move toward the roller. When the sheet 19 has been rolled around the roller an amount sufficient to cause the panel 24 to engage the mounting brackets 11 and 16, the housing 23 will be rocked counterclockwise a quarter turn from the position shown in FIGURE 6 to the position shown in FIGURE 4, thereby positioning the wall 24 below the roller in abutting relation with the rolled sheet and the wall 25 forwardly of the roller to conceal the latter and the mounting brackets from view. The rocking of the housing is facilitated by the anchoring of the free end of the sheet to the wall panel 24 between the side edges of the latter.

When the flexible sheet is rolled up, it should be rolled at such speed as to avoid latching of the roller latch pawls, thereby enabling the spring 7 constantly to exert a force on the housing tending to maintain the latter snugly against the wall 13. The capability of the spring to maintain the housing snugly against the wall is facilitated by the anchoring of the free end of the flexible sheet between the side edges of the panel 24.

As is indicated in FIGURE 4, the anchoring of the free end 22 of the flexible sheet to the panel 24 is at a point corresponding substantially to the radius of the roller 2 and the rolled sheet. The portion of the panel 24 from the anchoring means 28 to the free edge of the panel 24 thus comprises a lever arm cooperable with the force of the spring 7 to maintain the housing snugly against the wall 13.

Window shades, maps, projection screens, and the like usually have their operating rollers mounted above eye level. Consequently, the housing 23 may have two open

sides, thereby enabling the housing to be lighter in weight than if it had but one open side. Only one side of the housing need be open, however, so it is possible to include a panel or wall parallel to the wall 24 if it is desired for the purpose of protecting the rolled sheet from dust.

The disclosed embodiment is representative of a presently preferred form of the invention, but is intended to be illustrative rather than definitive thereof. The invention is defined in the claims.

What is claimed is:

1. A screen construction adapted for mounting on a vertical wall or the like and comprising a roller; means for rotatably mounting said roller on said wall; spring means acting on said roller for urging the latter to rotate in one direction; a flexible sheet having one of its ends free and its other end secured to said roller, whereby said sheet may be rolled upon itself about said roller; a plurality of panel members of greater length than the length of said roller and secured to one another to form a housing having at least one open side, said housing being of such size as to accommodate therein said roller, said rolled sheet and said mounting means; and means securing said free end of said sheet to one of said panel members between the side edges thereof and inwardly of said housing whereby said one panel member may abut said mounting means when the rolling of said sheet has been substantially completed, said sheet constituting the sole support for said housing, and said spring means being of such capacity as to be capable of exerting a rocking force on said housing and holding said housing against said wall when said one panel member abuts said mounting means.

2. The construction set forth in claim 1 wherein said panel members are two in number and together form a substantially L-shaped housing.

3. The construction set forth in claim 2 including substantially square end members at opposite ends of said panel members and closing the ends of said housing.
